CIRCUIT CONTROL APPARATUS

Nicholas J. Conrad, Winnetka, Ill., assignor to
Schweitzer & Conrad, Inc., Chicago, Ill., a cor-
poration of Delaware

Original application October 13, 1932, Serial No.
637,593, now Patent No. 2,134,470, dated October
25, 1938. Divided and this application Septem-
ber 8, 1938, Serial No. 228,980

12 Claims. (Cl. 175—294)

My invention relates, generally, to circuit control apparatus and it has particular relation to circuit interrupters.

The present application is a division of my copending application Serial No. 637,593, filed October 13, 1932, now Patent No. 2,134,470, issued October 25, 1938, and assigned to the assignee of this application.

The invention involves the use of a fusible conductor or link which performs the two-fold function of first detecting the presence of excessive current, reacting accordingly, and second, establishing a gap in which conductivity to current flow is destroyed.

The primary object of the invention is to provide a method of and means for increasing the range of interrupting capacity of devices of the foregoing type.

A further object is to secure increased capacity of interruption and/or certainty of operation by the use of fusible elements which, by themselves, are of insufficient capability to accomplish the desired purposes. For example, the capacity or characteristics of a power circuit, or the nature of the overload occurring therein, may be such that a fuse of a design or rating suitable for the circuits of a comparable voltage or rating finds difficulty in interrupting the current flow. By the use of my invention certainty of interruption is secured, without change of design or rating of the fuse employed. Hence, with a limited number of standard forms of fuses, automatic circuit interrupters of widely varying ability may be constructed to suit various requirements.

Another object of my invention is to effect the energization of an auxiliary circuit on operation of a circuit interrupter in a main circuit.

Still another object of my invention is to operate contact members as a result of the pressure generated on blowing of a fuse device of the blast action arc extinguishing type for connecting an auxiliary circuit for energization to a current source.

According to my invention a main interrupter, which automatically begins the action of mechanically opening the circuit upon the occurrence of overload, is bridged or shunted by a conducting path which is not adapted to carry the rated or normal current flow continuously, as soon as the main interrupter has reached a certain stage where the shunting conductor becomes effective.

According to this invention the main circuit interrupter normally carries all of the normal

or rated current flow. The auxiliary circuit interrupter normally carries none of the normal or rated current flow. These circuit interrupters are herein illustrated as liquid quenched fuses of a kind and type now on the market, 5 but the teachings of the present invention are not to be limited to the use of fuses of that kind or type, for the actions and functions which are secured by my invention may be attained through the use of different forms of fuses, as 10 will be apparent from the detailed specification appearing hereinafter.

The current flow which is normally carried by the circuit in which the interrupter of my invention appears, passes wholly through the 15 main fuse. Upon the occurrence of overload in the circuit the fusible link of the main fuse melts, and an arc tends to form. The spring then separates the terminals between which the arc exists, and there is injected into the arc an 20 arc extinguishing material the effect of which is a tendency to deactivate or deionize the gases which constitute the conducting path or substance of the arc. The combined effect of lengthening of the arc and deionization or de- 25 activation of the substance of the arc tends to render the conductive path less conductive to the flow of current. In other words, the potential drop across the arc tends to become greater. As a result of the pressure generated 30 by the evolution of the arc extinguishing gases the auxiliary circuit is completed around the main fuse and a conductive path is established through the auxiliary fuse. This conductive path has sufficient capacity for at least a brief 35 period, to diminish the current flow through the main fuse, whereby the combined action of lengthening the main arc and the deionization of the same results in putting out the main arc and transfer of such current flow as persists to 40 the shunt or auxiliary circuit. Meanwhile, the separation of the terminals of the main fuse has proceeded to such a point, and the arc extinguishing material has so acted, as to prevent 45 restriking of the arc in the main fuse.

The auxiliary or bridging circuit includes a certain amount of resistance, preferably in the form of a resistance wire such as a nickel chromium alloy, commonly sold on the market as "Nichrome" or "Chromel." Such resistance 50 tends to absorb a part of the potential drop and reduces current flow in this circuit to a value which may be easily interrupted by the auxiliary fuse.

The action is automatic. The separation of 55

the main fuse terminals tends to increase, perhaps not greatly, but very definitely, the potential drop across the main fuse terminals. The potential across the main fuse terminals is, of course, limited by the I. R. drop through the shunt circuit. This increase in potential drop forces the current through the auxiliary fuse in the shunt circuit. The shunt circuit has a certain thermal capacity which permits the establishment of a large enough current flow to permit the main fuse to open its circuit definitely and completely. The blowing of the auxiliary fuse takes sufficient time to allow the main arc to be extinguished. Then the progressive action of separating the auxiliary fuse terminals, injecting deactivating or deionizing arc extinguishing materials into the arc all cooperate to reduce and finally stop the flow of current in the auxiliary or shunt circuit. While the operations are described as occurring successively, the action as a whole is extremely rapid.

Now, in order to acquaint those skilled in the art with the manner of constructing and operating a device embodying my invention, I shall describe, in connection with the accompanying drawing, a specific embodiment of the same and the actions involved therein.

In the drawing:

Figure 1 is a diagrammatic illustration of an embodiment of my invention in which the pressure of the main fuse switches in the auxiliary fuse; and

Figure 2 is a side elevational view, partly in section, of one form of fuse which may be employed in the practice of my invention.

Referring first to Figure 1, the circuit interrupter is indicated between the conductors 1 and 2. Two liquid quenched fuses 11 and 12 are employed, the fuse 11 being connected through resistors 7 and 8 in parallel with the fuse 12. The proportions of the fuses may, for example, be as follows:

Fuse 11, $\frac{1}{2}$ ampere rating; fuse 12, 25 ampere rating, with the resistance of the resistors 7 and 8 consisting of 55.5 ohms.

Another example of proportioning for a different circuit, is as follows:

Fuse 11, 5 amperes rating; fuse 12, 100 amperes rating; with a resistance, in series, of 55.5 ohms.

The fuses 11 and 12 are preferably well known fuses now on the market. A suitable construction of fuse is shown in Figure 2. Various modifications of the fuse of Figure 2 are disclosed in my Patent No. 2,091,430, issued August 31, 1937. A suitable fuse for this purpose is also disclosed in my prior Patents No. 1,743,322 of January 14, 1930, and No. 1,834,578 of December 1, 1931. A sufficient description of such fuses and their operation is contained in said prior patents, and a brief description of the fuse shown in Figure 2 will suffice for present purposes.

The fuse comprises a glass sleeve 32 having metallic terminals at the ends thereof, the lower terminal 33 being in the form of a closed cap cemented on the glass sleeve, and the upper terminal 34 being in the form of a ferrule or sleeve likewise cemented on the upper end of the glass sleeve 32. The upper ferrule 34 is closed releasably by a cap 35 which, in case of excessive pressure and upon heavy blowing of the fuse, is adapted to be removed by the internal pressure. The sleeve or ferrule 34 is counterbored to provide a shoulder for mounting the upper terminal plate 36, which has slotted spring fingers pressing radially against the walls of the counterbore and

axially against the shoulder formed by the counterbore. A terminal stud 37 has a threaded shank extending through the plate 36 and it is held in place by the nut 38 threaded on said shank. A cooperating movable terminal 39 is mounted upon the upper end of the tension spring 40 through the medium of a spring head 42, to which the spring 40 is anchored. This spring head 42 has a threaded coupling with the terminal 39 and also has a socket 43 to which the flexible cable 10 44 is firmly anchored, electrically and mechanically. The cable 44 shunts the spring 40. A silver fuse wire 45 formed in the shape of a helix with the ends straightened out axially is connected between the movable terminal 39 and 18 the stationary terminal 37. A high tensile strength wire, preferably of nickel-chromium-alloy composition, indicated at 46, has loops formed at each end and these loops are engaged by pins 47 and 48 in the terminals 37 and 38, respectively. The ends of the fusible link 45 are mechanically anchored in slots in the terminals 37 and 38 to give a good mechanical and electrical anchorage, the edges of the slots being riveted or fastened over to grip the fuse wire along a considerable length. A liquid director 49 is supported on radially extending arms 50 upon the terminal 38. An explosion chamber is provided about the fusible element by means of the sleeve 52, the upper end of which is pressed into or otherwise anchored in the barrier plate 53, which barrier plate is threaded into the bore of the ferrule 34 to form a transverse wall. The upper end of the liquid director 49 embraces loosely but fairly closely the upper end of the explosion chamber 52. The glass sleeve is filled with arc extinguishing liquid to a point preferably just above the liquid director 49.

In operation, upon the occurrence of overload the fuse element 45 first melts, throwing the load 40 over upon the high tensile strength wire 46, termed the strain wire. Thereupon the strain wire melts and loosens the coil spring 40 to retract the terminal 39. At the same time arc extinguishing liquid is thrown into the explosion chamber 52, this stream of liquid being rapidly vaporized and to some extent broken down, and discharged upwardly into the chamber formed above the barrier plate 53. Here the vapors and gases are condensed and chilled, and if the arc 50 is interrupted before the pressure rises to too high a value the operation of interrupting current flow occurs without blowing of the cap 35. If the operation is severe, as in a short circuit on a system of large capacity, the pressure in the 55 fuse may rise to a value high enough to blow off the cap 35. The terminal plate 36 and terminal 37 may then also be expelled, and as the terminal 39 and liquid director 49 descend, vapors and gases of high pressure and very high velocity are 60 expelled through the explosion chamber, tending to deionize or deactivate the gases carrying the arc, to put out the same.

Referring now to Figure 1, it will be observed that the cap 35 is omitted from the fuse 12 and 65 that instead it is provided with an expandible member or bellows 78, which carries a contact 80 adapted to cooperate with the contact 82, forming the terminals of the gap 85'. In this case the pressure developed in the fuse 12 switches in the 70 shunt circuit by either bringing the contacts 80 and 82 into engagement or bringing them near enough to each other that the voltage drop across the gap will break the gap down and switch in the shunt circuit.

In operation the fuse 12 normally carries the entire current flowing through the circuit represented by the conductors 1 and 2. On the occurrence of an overload in this circuit, the fuse 12 operates as previously described. The pressure generated as a result of the blast action of the arc extinguishing material causes the expandible member or bellows 19 to be extended for closing the gap 55'. In such case the contact 80 may be moved into contact engagement with the contact 82. In either case the auxiliary circuit is then connected for energization to the current source represented by the conductors 1 and 2. The current flow is then transferred to the fuse 11 but it is materially limited by the resistors 7 and 8. The fuse 11 then operates in the manner previously described to open the path through the auxiliary circuit in which it is connected. Since the path between the conductors 1 and 2 has now been opened by the fuse 12 in the main circuit and the fuse 11 in the auxiliary circuit, no further flow of current takes place.

I do not intend to be limited to the specific details which I have above described. I do not wish to limit the arc extinguishing material, nor the specific form of the fuses, to the forms above described for the reason that those skilled in the art will at once appreciate that the mode of operation which I have explained may be embodied in forms structurally quite different but mechanically the equivalent of the aforesaid.

I claim:

1. A circuit control device comprising, in combination, a circuit interrupter of the blast action arc extinguishing type for connection in a power circuit, an auxiliary circuit including a resistor normally out of said power circuit, and contact means arranged and adapted to connect said auxiliary circuit in said power circuit in shunt circuit relation to said circuit interrupter, said contact means being operated by the blast occurring on operation of said circuit interrupter.

2. A circuit control device comprising, in combination, a circuit interrupter of the blast action arc extinguishing type for interconnecting a pair of circuit terminals, a member operatively connected to said circuit interrupter and disposed to be moved on the occurrence of a blast initiated by operation of said circuit interrupter, contact means operated by said member, and an auxiliary circuit including a resistor normally out of the circuit between said circuit terminals and arranged and adapted to be connected in shunt circuit relation to said circuit interrupter on operation of said contact means.

3. A current interrupter comprising, in combination, a fuse device for connection in a power circuit, an auxiliary circuit including a resistor normally out of said power circuit, and contact means arranged and adapted to connect said auxiliary circuit in said power circuit in shunt circuit relation to said fuse device, said contact means being operated as a result of the blowing of the fusible element of said fuse device.

4. A current interrupter comprising, in combination, a fuse device for interconnecting a pair of circuit terminals, a readily deformable member operatively connected to said fuse device and disposed to be deformed on the blowing of the fusible element of said fuse device, contact means operated by said deformable member, and an auxiliary circuit normally out of the circuit between said circuit terminals and arranged and adapted to be connected in shunt circuit relation

to said fuse device on operation of said contact means.

5. A current interrupter comprising, in combination, a fuse device of the blast type for interconnecting a pair of circuit terminals, an expandible member operatively connected to said fuse device and disposed to be extended on operation of said fuse device, contact means operated by said expandible member, and an auxiliary circuit normally out of the circuit between said circuit terminals and including a fuse device arranged and adapted to be connected in shunt circuit relation to said first mentioned fuse device on operation of said contact means.

6. A current interrupter comprising, in combination, a fuse device of the blast type for interconnecting a pair of circuit terminals, a member operatively connected to said fuse device and disposed to be moved on the occurrence of a blast initiated by operation of said fuse device, contact means operated by said member, and an auxiliary circuit normally out of the circuit between said circuit terminals and including a resistor arranged and adapted to be connected in shunt circuit relation to said fuse device on operation of said contact means.

7. Circuit control apparatus comprising, in combination, a circuit interrupter of the blast action arc extinguishing type for connection in an electric circuit, an auxiliary circuit, and contact means arranged and adapted to connect said auxiliary circuit in shunt circuit relation with said circuit interrupter, said contact means being operated by the pressure generated by the blast occurring on operation of said circuit interrupter.

8. Circuit control apparatus comprising, in combination, a circuit interrupter of the blast action arc extinguishing type, readily deformable means operatively connected to said circuit interrupter and disposed to be deformed by the pressure created by the blast resulting from operation thereof, contact means operated by said deformable means, and an auxiliary circuit arranged to be connected in shunt circuit relation with said circuit interrupter on operation of said contact means.

9. Circuit control apparatus comprising, in combination, a fuse device of the blast type, readily deformable means operatively connected to said fuse device and adapted to be deformed by the pressure generated by the blast resulting from operation thereof, an auxiliary circuit, and contact means operable as a result of deformation of said deformable means for connecting said auxiliary circuit in shunt circuit relation with said fuse device.

10. Circuit control apparatus comprising, in combination, a fuse device of the blast type, an expandible bellows operatively connected to said fuse device and adapted to be expanded by the pressure generated by the blast resulting from operation thereof, an auxiliary circuit, and contact means operable by expansion of said bellows for connecting said auxiliary circuit in shunt circuit relation with said fuse device.

11. Circuit control apparatus comprising, in combination, a liquid fuse device adapted to be mounted in an upright position for connection in a circuit to automatically interrupt the same on the occurrence of a predetermined overload, a flexible bellows hermetically sealed to one end of said fuse device and forming therewith a unitary device, said flexible bellows itself serving to close said one end of said fuse device and expanding as a result of the pressure generated thereby on

blowing thereof, and means operated by said flexible bellows on expansion thereof.

12. Circuit control apparatus comprising, in combination, a fuse device of the blast action arc extinguishing type for connection in a circuit to automatically interrupt the same on the occurrence of a predetermined overload, a flexible bel-

lows closing one end of said fuse device and located directly in the path of the blast generated on blowing of said fuse device and adapted to expand as a result of the pressure of said blast, and means operated by said flexible bellows on expansion thereof.

NICHOLAS J. CONRAD.
